UNITED STATES PATENT OFFICE.

WILLIAM H. GREENWOOD, OF EVERETT, MASSACHUSETTS.

GUARD FOR INCANDESCENT ELECTRIC LAMPS.

No. 906,411.

Specification of Letters Patent.

Patented Dec. 8, 1908.

Application filed November 7, 1907. Serial No. 401,519.

To all whom it may concern:

Be it known that I, WILLIAM H. GREENWOOD, a citizen of the United States of America, and a resident of Everett, in the county of Middlesex and State of Massachusetts, have invented certain new and useful Improvements in Guards for Incandescent Electric Lamps, of which the following is a specification.

10 This invention relates to protectors or guards for the bulbs of incandescent electric lamps and it has for its object the production of a protector which may be rigidly secured to the socket of such a lamp and 15 depend therefrom in such a manner as to protect the bulb from breakage.

The invention consists in certain novel features of construction and arrangement of parts which will be readily understood by 20 reference to the description of the drawings and to the claims hereinafter given.

Of the drawings: Figure 1 represents a plan view of a protector embodying the features of the present invention. Fig. 2 represents an elevation of the same applied to a socket of an incandescent electric lamp. Fig. 3 represents a vertical section of the protector on line 3—3 on Fig. 1 with the divided top open. Fig. 4 represents a horizontal section on line 4—4 on Fig. 2. Fig. 5 represents a sectional detail of the latch for securing together the divided top, on line 5—5, Fig. 1, and Fig. 6 represents a sectional detail of the same on line 6—6 on Fig. 1.

35 Similar characters designate like parts throughout the several figures of the drawings.

In the drawings, 10 represents a suitable openwork wire cage consisting of rings 11, 40 12, 13, and 14 which are connected together by the bent vertical wires 15 extending from the rings 11 to the ring 14. To the ring 11 are hinged at 16 and 17 the two parts 18 and 19 of a divided top, each part 18 and 19 45 consisting of a semi-annular plate having a downwardly extending flange 20 which is adapted to surround when in closed position the ring 11. At 21 is pivoted to each of the parts 18 and 19 a latch 22 provided 50 with a thumb piece 23 by which the latch may be moved about said pivot 21. This latch has a projecting tongue 24 adapted to engage with an upturned lip 25 on the opposing part 18 or 19 of the divided top, all 55 as clearly shown in the drawings.

It will be noted by an inspection of the

drawings that the preferred form is to have one latch upon the part 19 engaging with a lip 25 upon the part 18 while the other latch on the opposite side of the axis of the protector is pivoted to the part 18 and engages with a lip on the part 19. It is obvious, however, that both of the latches might be pivoted to the same part of the divided top and engage with lips upon the co-acting part. 65 Each of the members 18 and 19 is provided with an upwardly projecting flange 26 which is adapted to grip the socket 27 of an incandescent electric lamp when the members 18 and 19 are closed and locked by means of 70 the latch 22, these members rigidly securing the protector in position. Each of the latches 22 is provided with a downwardly and inwardly turned lip 28 which passes beneath the ring 11 and supports the portion of the 75 ring intermediate the hinges 16 and 17. To the ring 13 is secured the cradle 29 which is made of spring wire and has a part 30 which engages the bulb 31 of an incandescent electric lamp, thereby tending to center the 80 bulb in the protector 10 and preventing the bulb from coming in contact with the guard protector 10 when the latter is subjected to a blow.

By such a construction as is herein shown 85 and described a bulb to an incandescent electric lamp may be securely protected from any injury and reduce the breakage of such bulbs in a factory or other similar place to a minimum.

It is obvious from an inspection of the drawings that the cage itself, being made integral, of wire, all connected together to the cage itself, is of great rigidity and at the same time having the top piece made of two 95 members 18 and 19 hinged to the top of the cage the lamp is more readily inserted in the guard and the guard itself may be more firmly secured to the socket of the lamp than by methods heretofore in use.

It is believed that the many advantages of a protector of such a construction as is herein shown and described and the operation of the same will be fully apparent without any further description.

Having thus described my invention, I claim:

1. A lamp protector consisting of a wire-work cage terminating at the top in a continuous ring; a divided cover each part of 110 which is pivoted to the top of said cage consisting of two semi-annular plates each of

which is provided with a semi-annular wall adapted to encompass one-half of the lamp socket; and means for securing said semi-annular plates to said cage.

5. 2. A lamp protector consisting of a wire-work cage terminating at the top in a continuous ring; a divided cover to the top thereof consisting of two semi-annular plates each of which is provided with a semi-annular wall adapted to encompass one-half of the lamp socket; and a hinge midway of the ends of each semi-annular plate for securing it to said cage.

15. 3. A lamp protector consisting of a wire-work cage terminating at the top in a continuous ring; a divided cover to the top thereof consisting of two semi-annular plates each of which is provided with a semi-annular wall adapted to encompass one-half of the lamp socket; hinges for securing said semi-annular plates to said cage; and movable means on each semi-annular plate adapted to engage a member on the other plate to lock said plates together.

25. 4. A lamp protector consisting of a wire-work cage terminating at the top in a continuous ring; a divided cover to the top thereof provided with an opening therethrough the walls of which are adapted to encompass the lamp socket; hinges for securing said divided top to said cage; and means for locking together the two parts of said top and said top to said cage.

35. 5. A lamp protector consisting of a wire-work cage terminating at the top in a continuous ring; a divided cover to the top thereof provided with an opening therethrough the walls of which are adapted to encompass the lamp socket; hinges for securing said semi-annular plates to said cage; and a pivoted latch on one of said plates

adapted to engage a projecting member on the other plate for locking together the two parts of said top.

6. A lamp protector consisting of a wire-work cage terminating at the top in a continuous ring; a divided cover to the top thereof provided with an opening therethrough the walls of which are adapted to encompass the lamp socket; hinges for securing said divided top to said cage; and pivoted latches for locking together the two parts of said top and said top to said cage.

7. A lamp protector consisting of a wire-work cage terminating at the top in a continuous ring; a divided cover to the top thereof provided with an opening therethrough the walls of which are adapted to encompass the lamp socket; depending spring members within said cage adapted to embrace said lamp and center it in said cage; hinges for securing said divided top to said cage; and means for locking together the two parts of said top and said top to said cage.

8. A lamp protector consisting of a wire-work cage; a divided cover to the top thereof provided with an opening therethrough the walls of which are adapted to encompass the lamp socket; a projection on one of said cover plates; and a pivoted latch on the other plate provided with a member adapted to engage said projecting member to lock the two plates together and also provided with a lip adapted to normally lock said cage to said divided cover.

Signed by me at Boston, Mass., this 1st day of April, 1907.

WILLIAM H. GREENWOOD.
